UNITED STATES PATENT OFFICE.

GIUSEPPE MATRICARDI, OF PALLANZA, ITALY, ASSIGNOR TO SOCIÉTÉ HARLÉ & CIE.,
OF PARIS, FRANCE, A CORPORATION OF FRANCE.

ROPE FOR HAULAGE AND OTHER PURPOSES.

1,061,252.

Specification of Letters Patent.

Patented May 6, 1913.

Application filed April 12, 1910. Serial No. 555,086.

To all whom it may concern:

Be it known that I, GIUSEPPE MATRICARDI, engineer, of Pallanza, Italy, have invented a new and useful Improvement in Ropes for 5 Haulage and other Purposes, which improvement is fully set forth in the following specification.

This invention has for its object to provide an improved wire rope having upon it 10 knobs or bosses. The rope is especially useful for raising heavy objects.

In the accompanying illustrative drawings, Figure 1 shows a portion of a rope with a boss in the course of manufacture, 15 and Fig. 2 shows the same portion of a rope with the boss complete.

a is a wire rope to be provided at various points with bosses. For this purpose the strands are first loosened, as shown in Fig. 20 1, the hempen core being preferably removed at these points. Iron or other suitable pins *b* are then inserted between the strands and the swells thus obtained are placed in a mold of the size of the boss it is desired to 25 obtain and molten metal is then run in.

The mold is preferably of ovoid shape and the iron pins *b* are preferably first tinned or coated with a metal adapted to adhere both to the pins and the metal run in. The bosses 30 thus obtained are all of equal size and of regular shape and, as the cast metal penetrates between the strands and all around the pins, thus impregnating the heterogeneous mass and rendering it impossible for the 35 bosses to become loose and slip upon the rope.

Having now particularly described and ascertained the nature of my said invention and in what manner the same is to be performed, I declare that what I claim is:

1. A wire rope provided with knobs or bosses formed of metal pins inserted between the strands of the rope, whose projecting ends are surrounded with a mass of metal substantially as described. 40

2. The method of manufacturing a wire rope provided with knobs or bosses which consists in loosening the strands, removing the core, inserting projecting pins between said strands and casting a mass of metal 50 around said projecting pins, substantially as described.

3. The method of manufacturing a wire rope provided with knobs or bosses, which consists in loosening the strands, removing 55 the core, inserting projecting pins between said strands, said pins being provided with a coating of metal adapted to adhere to the pins and, finally, casting a mass of metal around said projecting pins, said metal being such as will adhere to the coating metal 60 of the pins.

In testimony whereof I have signed this specification in the presence of two subscribing witnesses.

GIUSEPPE MATRICARDI.
